PATRICK B. DELANY, OF SOUTH ORANGE, NEW JERSEY.

TELEGRAPHIC TRANSMITTER.

1,100,357.

Specification of Letters Patent. Patented June 16, 1914.

Application filed April 26, 1906, Serial No. 313,738. Renewed November 5, 1913. Serial No. 799,375.

To all whom it may concern:

Be it known that I, PATRICK B. DELANY, a citizen of the United States, residing in South Orange, county of Essex, State of New Jersey, have invented certain new and useful Improvements in Telegraphic Transmitters, of which the following is a specification.

This invention relates primarily to that class of transmitters in which a series of dots representing a signal character or letter is automatically formed by one movement of a key lever, the number of dots depending upon the period of time during which the lever is held in dot position. Dashes are formed in such instruments by a movement of the key lever in opposite direction, or by actuation of some supplementary dash contact device. The utility and general purpose of instruments of this character are well understood. The particular class of such instruments to which this invention relates is that in which the dot forming member is a vibrator resembling a reed; but capable of vibrations of such period and amplitude as to satisfactorily transmit successions of dot signals or impulses. Such a vibrator when set into vibration by movement of the transmitting key will, by its substantially uniform continued action, effect transmission of dots in regular succession.

A primary object of this invention is to make the load upon the key as light as possible; to eliminate from the key the jars or vibrator effects of the vibrator and to impart to the vibrator abrupt, quick impacts that set it into vibration and the force of which is determined by the operator.

A further object is to reduce to a minimum liability of splitting the dot impulses, and this feature of the invention is applicable to auto-dot key transmitters of various kinds or type, many of which are now known and some of which are now in practical use.

The invention comprises the employment of a vibratory member consisting of a rigid, or relatively rigid, lever, rocking about an axis and carrying at one end a resilient vibrating blade to which a weight, preferably movable for adjustment, is applied. A spring holds this vibratory member in normal position with the resilient vibrating blade or some part beyond the point of connection with the rigid lever against a stop. When acted upon by the key lever, the relatively rigid part of the vibratory member is

thrown against a rigid limiting stop, impact upon which, together with the co-incident momentum of the weighted blade, sets the latter into vibration and causes it to make and break the circuit at a suitable yielding contact, to so form or transmit a succession of dot signals, that continues during the time that the parts remain in dot forming position. To prevent splitting of the dot impulses, there are included in the circuit a pair of unyielding contacts that are positively separated at the initial movement of the key toward normal position.

In the accompanying drawings: Figure 1 is a diagrammatic plan view showing an arrangement for dot and dash transmission according to the Morse or other codes; and Fig. 2, is a similar view showing an arrangement for cable transmission in which dot impulses only are sent into the line.

Referring to Fig. 1, *a* is a key lever rocking about a vertical axis *b*. It is provided at one end with a thumb plate *c* and finger head *d* by which it may be moved either to the left or right of normal central position in which it is maintained by oppositely acting springs *e*. Mounted parallel with the rear portion of the key lever is a lever arm *f* rocking about a vertical axis *g*, and to one end of which there is rigidly secured a flat spring vibrating blade *h* enlarged at its outer end *i* and having there applied an adjustable weight or bob *j*. A spring *k* applied to the lever arm *f* normally draws the resilient vibratory part against a limiting stop *m* which also serves to deaden or suppress vibration when the parts return to normal position. On the other side of the vibratory member is a rigid limiting stop *n* against which the rigid lever arm *f* abuts, and also a yielding electrical contact *o* with which the resilient vibratory part is adapted to make and break contact. On the rear end of the key lever is a lateral projection *p* which when the parts are all in normal position as shown in the drawings, is in contact with the end of the lever *f* that extends in rear of its axis *g*.

The circuit connections are as follows: a source of energy or main battery *M B* has one pole grounded, and its other pole connected to the yielding contact *o*, stop *n* being connected to line. When the front end of the key lever is thrown to the right, projection *p* acts upon lever arm *f* and throws it abruptly against stop *n*. The vibratory

blade *h* is abruptly thrown into vibration, primarily by impact of lever *f* against stop *n*. The operator may quickly release the key if a single dot only is to be transmitted, or may hold it in position until the desired number of dots have been transmitted by the automatic vibration of the part *h*, *j*. The dots may as usual be audibly indicated to the operator by a local instrument in circuit. When the required number of dots has been effected and the operator releases the key, the first effect is to break the circuit at *b*, *n*, and an additional dot cannot be transmitted even if the vibrator *h* should after release of the key come against contact *o*. When the key is released spring *h* restores the vibratory member to normal position and vibration of the elastic vibrator *h* is suppressed when it comes against its stop *m*. The distances between the axis of the key lever and projection *p* and the outer end of the lever may be such as to afford desirable leverage under which the projection *p* acts upon lever arm *f*. Similarly the length of lever arm *f* on each side of its pivot may be so proportioned as to afford desired results. To transmit a dash, the outer end of the key lever is moved to the left against stop *q* which is connected with the main battery the key lever being connected to line.

Fig. 2 shows substantially the same arrangement of parts except that they are duplicated on each side of the key lever. This is for cable transmission. Parts corresponding with those shown in Fig. 1 bear the same letters respectively with the addition of the exponent "2." When the outer end of the key lever is moved to the right, dot impulses of uniform polarity representing dot signals are sent into the line; and when it is thrown to the left, similar impulses of uniformly opposite polarity representing dash signals are sent to line. *l b* is a local battery one pole of which is connected to the lever arms *f*, *f'*, and the opposite pole through the coils of magnets *r*, *s*, and thence respectively with contacts *o*, *o'*. *M B* is the main battery. *r*, *s* form parts of the well known pole changing arrangement which does not require a description. In this arrangement, the springs *k*, *k'* act through the arms *f*, *f'* to hold the key lever in normal central neutral position.

I claim as my invention:

1. A telegraphic transmitter, comprising a key, an automatic circuit controller set into operation on movement of the key to form a succession of dot signals, a circuit contact with which it coöperates, and circuit contacts closed by movement of the key to set the controller in operation and opened by reverse movement of the key.

2. A telegraphic transmitter, comprising a key, an automatic vibrator set into opera-

tion on movement of the key to form a succession of dot signals, a circuit contact with which it coöperates, and circuit contacts closed by movement of the key to set the vibrator in operation and opened by reverse movement of the key.

3. A telegraphic transmitter, comprising a movable part, an automatic dot transmitter set into operation on movement thereof, and circuit closing contacts closed by said part when moved to start the dot transmitter and opened by it when moved to stop transmission of dots.

4. A telegraphic transmitter, comprising a transmitting key, a pivoted lever adjacent the key and adapted to be moved by it, a stop against which the lever is moved when actuated by the key, an elastic vibrator carried by the lever and set into vibration when the lever is arrested by its stop, and a dot transmitting contact through which the vibrator automatically closes and opens the circuit to transmit a succession of dot signals.

5. A telegraphic transmitter, comprising an automatic dot transmitting vibrator, a transmitting key lever acting when operated for dot transmission to impart to the vibrator an impulse of movement, a rigid stop against which the vibrator intermediate its ends is thrown and held by the key lever and a dot transmitting contact at which the circuit is opened and closed by the vibrations of the free end of the vibrator while the vibrator is held against said stop.

6. A telegraphic transmitter, comprising an automatic dot transmitting vibrator consisting of a stiff pivoted part and an elastic weighted vibratable part carried in the free end of the stiff part, a key lever adapted, when operated for dot transmission, to impart to the vibrator an impulse of movement, a fixed stop against which the said stiff part is thrown by the key lever and a dot transmitting contact coöperating with said elastic vibratable part.

7. A telegraphic transmitter, comprising the combination of a key lever pivoted upon a vertical axis, a lever arm also pivoted upon a vertical axis and adapted to be actuated by the key lever, a stop for limiting the movement of the lever arm when so actuated, an elastic vibrator carried by said arm, a contact through which it automatically transmits dots, a stop against which the vibrator bears when in inactive position and a spring tending to draw it against such stop.

8. A telegraphic transmitter, comprising a pivoted key lever, a lever arm pivoted independently adjacent thereto, a surface on the key lever against which the lever arm is normally drawn by its retractile spring, a stop against which the lever arm is thrown when actuated by the key lever, an elastic

vibrator carried by the lever arm and set into vibration when said arm is arrested by its stop, a contact through which the vibrator automatically transmits dots and circuit contacts closed by the key when moved to actuate the lever arm and opened on reverse movement of the key.

9. A telegraphic transmitter comprising a key lever, a separately mounted lever having a vibratile part, and means whereby the said separately mounted lever is set vibrating to transmit dots automatically by being pushed by the key lever.

10. A telegraphic transmitter comprising a key lever, a separately mounted lever having a rigid part and a flexible part, a stop for said rigid part and means whereby said flexible part transmits dots while said rigid part is held against said stop by said key lever.

In testimony whereof, I have hereunto subscribed my name.

PATRICK B. DELANY.
